SELECTIVITY CONTROL SYSTEM

Winfield R. Koch, Camden, N. J., assignor to Radio Corporation of America, a corporation of Delaware

Application May 31, 1935, Serial No. 24,217

12 Claims. (Cl. 250—20)

The present invention relates to a selectivity control system for radio receiving apparatus and the like, and more particularly, relates to a system of that character for application to the tuned 5 signal receiving circuits wherein a wide range of selectivity control is required.

It is a primary object of the present invention to provide an improved selectivity control system for radio receiving apparatus and the like, which 10 may be applied to tuned circuits and interstage coupling means in the high frequency portion of a radio receiver to secure improved selectivity control thereof through a wide range of control of effective anode-cathode impedance of an electric 15 discharge control device included in shunt with said circuits and means.

In accordance with the invention, instead of utilizing the plate impedance of a triode or pentode tube to produce damping in a tuned circuit 20 and thus secure selectivity control by controlling the grid bias, the principle of negative regeneration is used to secure improved results thereover. It has been found that, with the triode used as an 25 impedance load for a tuned circuit, some distortion may occur when the tube is biased near the cut-off point of the anode current, and the lowest shunt resistance which may effectively be placed across the tuned circuit with present tubes is not sufficiently low to provide proper control of the 30 selectivity.

However, the importance of low effective impedance secured does not lie only in the selectivity change, but also in the very effective volume control action of the shunt load.

Accordingly, it is a further object of the present 35 invention to provide an improved selectivity control system providing a load across a tuned circuit, which system embodies a pentode type of tube to provide an effective load which may be made less than 1,000 ohms and may readily be varied by 40 simple control means in the range of 1,000 to 10,000 ohms. It has been found that, by utilizing the pentode type of tube, the desired effective 45 control may be obtained without introducing distortion of the signal by operation of the selectivity control means.

The invention will, however, be better understood from the following description when considered in connection with the accompanying 50 drawing, and its scope will be pointed out in the appended claims. In the drawing,

Figure 1 is a schematic circuit diagram of a 55 radio receiving circuit having a selectivity control system embodying the invention;

Fig. 2 is a similar schematic diagram illustrating a modification of the system embodying the invention as applied to a radio receiving circuit of a different type; and

Fig. 3 is a curve diagram illustrating certain 60

operating characteristics of the control systems of Figs. 1 and 2.

Referring to Fig. 1, an intermediate frequency amplifier is illustrated comprising a tuned intermediate frequency input transformer 5 connected between the grid 7 and the cathode 9 of an intermediate frequency amplifier tube 11 of the pentode type. The type grid circuit is returned through a lead 13 to a common ground lead 15 which is also the common plate and grid return 10 circuit. The receiver and the return circuit for the grid is completed through a suitable self-bias resistor 17.

The first stage intermediate frequency amplifier tube 11 is coupled to a second intermediate frequency amplifier tube 19 through a suitable tuned interstage coupling transformer 21 and it will be noted that the tube is the same as the tube 11 being of the screen grid pentode type provided with biasing potential from a self-bias resistor 23 connected 15 with the common return circuit lead 15.

The intermediate frequency amplifier is provided with input terminal leads 25 and output terminal leads 27, one of which is the positive anode potential supply lead derived from a suitable source of direct current represented by the voltage divider resistor 29. It will be noted that the common return lead 15 is connected to an intermediate tap 31 on the divider resistor, so that, between the negative supply terminal indicated 20 at 33 and the tap 31, a source of negative potentials is available with respect to the cathodes of the receiving system. The screen grid connection is made through a suitable lead 35 to a voltage supply point 37 while anode potentials are provided through the lead indicated at 39. The voltage divider resistor represents any suitable source of operating potentials for the electric discharge device of the system and, since an 25 amplifier of this character is known and well 30 understood, further description is believed to be 35 unnecessary.

For the control of selectivity in a system of the character shown, one or more of the tuned circuits may be loaded in accordance with the invention 40 and, in the present example, the tuned output circuit of the first intermediate frequency amplifier is arranged to be controlled thereby to control the 45 selectivity of the system. The output circuit comprises the primary winding 41 of the intermediate frequency transformer 21 and the shunt tuning condenser 43. The anode or high potential side of the circuit is connected through a lead 45 to a screen grid pentode electric discharge device or tube 47 with the plate 49 connected to 50 the lead 45 and the cathode 51 thereof connected preferably through a self-biasing resistor 53 to the ground lead 15 whereby the device 47 forms 55 a high frequency load across the tuned circuit. The anode circuit of the tube 47 is, therefore, 60

completed through the same primary winding 41 as is that of the amplifier tube 11, and variations in the anode current flow serves to variably load the tuned circuit.

5 In order to control the load current, the inner or control grid 55 of the selectivity control tube 47 is connected through a lead 57 and a filter resistor 59 with the negative or return lead 15 through a source of negative biasing potential which may be varied and which is, therefore, included in the grid circuit in addition to the negative potential provided by the self-bias resistor 53.

10 The source of additional potential for controlling the tube may be derived selectively from either of two sources, through a selector switch 61 to which the resistor 59 is connected by a lead 63. The selector switch has one contact 65 leading to a suitable source of automatic volume 15 control voltage, as indicated in the drawing, and a second contact 67 connected through a lead 69 with a variable contact 71 on the negative potential supply portion of the power supply or 20 voltage divider resistor 29 between the terminals 25 31 and 33.

25 As shown in the drawing, the switch 61 is connected to the contact 67 to receive manually variable control potentials from the contacts 71 whereby the selectivity of the system may be 30 varied by manual means. The automatic volume control voltage may be utilized for the same purpose by moving the switch to the contact 65. Screen grid potential is supplied to the device 47 to a supply lead 73 connected to a movable contact 35 75.

30 The selectivity control voltage derived from the automatic volume control circuit or from the manually controllable selectivity control voltage at 71 must become more negative to make the 40 transformer 21 broad in its tuning characteristic. By utilizing a pentode type tube at 47, the manual control may also be provided for varying the contact at 75 to vary the screen grid voltage. By varying the control grid voltage or 45 the screen grid voltage the mutual conductance of the selectivity control tube 47 is varied.

45 Referring to Fig. 3, the variation of mutual conductance with variations in control grid voltage is indicated by the curve 77, while the loading effect or effective or operating plate impedance of the tube 47 is indicated by the curve 79. It will be seen that the mutual conductance is 50 variable over a relatively wide range to provide a similar smooth wide control range of the effective plate impedance.

55 The control effect is further enhanced by connecting a coupling condenser 81 between the control grid 55 and the tuned circuit comprising the condenser 43 and the inductance 41, the coupling condenser being connected from a high potential point 83 on the circuit through a connecting lead 85. The reactance of the condenser 81 is relatively low with respect to the resistance 60 59 in the grid circuit. In general, preferably, the resistance should be high and the condenser should have a reactance less than a few percent of the resistance used.

65 With this circuit arrangement, any voltage 70 appearing across the tuned circuit 43-41 will be impressed upon the grid of the selectivity control tube through the coupling condenser 81. Because of the amplifying property of the selectivity control tube, a large voltage, 180° out of phase with the impressed voltage, will appear

75 in the plate circuit of the tube. This will tend to oppose and reduce the original voltage, which in effect, is the same as adding resistance to the tuned circuit to broaden it. The higher the mutual conductance of the selective control tube 5 the more this resistance damping will be. Therefore, by varying the mutual conductance of the tube, the broadening effect on the tuned circuit may be controlled and, with the circuits, as hereinbefore described, this may be caused to operate 10 manually, or automatically with variations in signal strength.

15 A system in accordance with the invention, therefore, provides means for variably loading a tuned circuit over a relatively wide range of 15 impedance by varying the mutual conductance of a pentode electric discharge device, the anode-cathode space path of which is in the loading circuit, and permitting the tube further to amplify signals from the tuned circuit and to apply 20 said signals in opposing relation to the original signal voltage, thereby to broaden the tuning of said circuit.

25 In this manner the tuned circuit of a radio receiver or a plurality of said circuits may be 25 made automatically responsive in any desired degree to variations in signal strength, whereby the said circuit or circuits are more broadly tuned in response to increased average signal strength and the degree of response may simultaneously be placed under manual or automatic control such as the said variations in signal strength through automatic volume control 30 means.

35 Furthermore, since, as indicated in Fig. 3, the response characteristic 77 has a long cut-off range, distortion is substantially eliminated while the control characteristic 79 is substantially smooth and gives in effect a "straight line" 40 control.

45 While the invention has been described in connection with an intermediate frequency amplifier and is preferably so applied in the usual radio receiver, and while it has further been described as being responsive to increases in negative potential from a controlling circuit, it may 50 also be applied to other receiving circuits and may be made responsive to a control voltage which is positive as applied to the control grid of the selectivity control tube. In other words, an increasing positive control voltage may be 55 applied to the system to render the control grid of the selectivity control tube more positive to broaden the frequency response characteristic of the tuned receiving circuit and such a system is 60 shown in Fig. 2 to which attention is now directed.

65 A radio frequency amplifier is provided in connection with an antenna or other signal source 65 87 provided with the usual input coupling transformer 89 having a secondary 91 tuned by a variable condenser 93 connected therewith through a stopping condenser 95. The high potential side of the tuned circuit comprising the lead 97 is connected to the control grid 99 of a radio frequency amplifier tube 101 of the pentode type 70 through a coupling condenser 103 and grid leak resistor 105. The amplifier tube 101 is provided with a radio frequency output circuit comprising a tuned coupling transformer 107.

75 Across the tuned circuit is connected the anode-cathode space path of a selectivity control tube 109 of the screen grid pentode type, having the anode 111 connected with the high potential side 80 or lead 97 of the tuned circuit 91-93-95 and 75

having the cathode 113 connected through a self-bias resistor 115 with the opposite or ground side of the circuit through suitable grounds 117 and a lead 119. Anode potential is supplied through a lead 121 and the secondary 91 to the anode 111, the anode voltage being isolated from the grid 99 by the coupling condenser 103.

In the present example, the control or inner grid 123 of the selectivity control tube 109 is coupled through a coupling condenser 125 of relatively low capacity to the high potential side 97 of the tuned circuit 91-93-95. Grid biasing potential is supplied to the control grid 123 through a grid leak resistor 127 which also provides a filtering and isolating means for the grid. The grid leak resistor is in turn connected through a lead 129 to a manual selectivity control device comprising a potentiometer 131, the variable contact 133 of which is connected to the lead 129 and the potentiometer in turn receives a fixed direct current potential or voltage from supply terminals indicated at 135 through leads 139. With this arrangement, the device 131 is readily adapted to be placed at a remote point for remote control of selectivity by extending the leads 129 and 139.

It will be noted that the upper terminal 141 of the volume control potentiometer 131 is positive while the lower terminal 143 is negative. The potential, therefore, applied to the control grid 123 from the contact 133, is caused to increase in opposition to the biasing potential derived from the self-bias resistor 115, as the contact 133 is moved toward the positive terminal 141.

In other words, as the control contact 133 is moved toward the contact 141, the control grid 123 becomes less negative, or if the selectivity control voltage between the terminals 135 is increased the control grid 123 may be said to become more positive and, in either event, the arrangement is such that the tuning response characteristic of the tuned circuit, across which the space current path of the device 109 is connected and to which the control grid is coupled, becomes broader thereby decreasing the selectivity of the receiving circuit.

In this system the selectivity is greatest when the impedance across the tuned circuit is the highest. Therefore, the circuit becomes broad in its response as the control voltage increases in a positive direction. The amplifying property of the tube is utilized in the same manner as described in Fig. 1 to provide a further control effect, whereby the effective resistance across the tuned circuit may be reduced substantially below 1,000 ohms.

In order that the selectivity control tube 109 may be biased to cut-off with no signal, the terminal 143 of the control device 131 is connected to a negative supply lead 137 having a negative potential with respect to the cathode 113 of approximately 45 volts for a device of the character shown.

With no signal the selectivity is highest since the loading of the tuned circuit is substantially zero.

In this circuit as in the circuit of Fig. 1, signal voltages appearing across the tuned circuit 91-93-95 will be impressed upon the control grid 123 of the selectivity control tube 109 and, because of the amplifying characteristic thereof, relatively high voltage, 180° out of phase with the impressed signal voltage, will appear in the plate circuit of the tube and will be opposite the original voltage in effect to said resistance to

the tuned circuit to broaden it. This circuit, therefore, differs from the circuit of Fig. 1 in that the selectivity is highest when the impedance across the primary 41 of the transformer 21 is lowest, whereas in the present circuit the selectivity is higher when the impedance across the secondary 91 is highest.

I claim as my invention:

1. In a radio receiving circuit, the combination with a tuned high frequency transformer, of a pentode electric discharge device having its anode-cathode impedance connected effectively in shunt relation to a tuned signal circuit including said transformer, means for coupling the control grid of said device to the high potential side of said circuit to receive signal energy therefrom, and means for applying a control voltage to said control grid to adjust the mutual conductance of said device and the selectivity of said circuit. 20

2. In a radio receiving system, the combination with a tuned high frequency signal circuit comprising an inductance and a shunt condenser and a coupling winding associated with said inductance, of a pentode electric discharge device having an anode connected directly with said tuned circuit and in series with the inductance thereof for conveying anode current thereto, and having a cathode connected with the opposite side of said circuit, and said device having a control grid associated with the cathode and a screen grid interposed between said control grid and the anode, means providing a series relatively high resistance in circuit between the grid and cathode, means for coupling said control grid to the high potential side of said tuned circuit comprising a condenser of relatively low reactance with respect to said resistance in series with the grid, and means for supplying a controlling potential through said resistance to the control 40 grid. 30

3. In a radio receiving system, the combination with a tuned high frequency signal circuit comprising an inductance and a shunt condenser and a coupling winding associated with said inductance, of a pentode electric discharge device having an anode connected directly with said tuned circuit and in series with the inductance thereof for conveying anode current thereto, and having a cathode connected with the opposite side of said circuit, and said device having a control grid associated with the cathode and a screen grid interposed between said control grid and the anode, means providing a series relatively high resistance in circuit between said grid and cathode, means for coupling said control grid to the high potential side of said tuned circuit comprising a condenser of relatively low reactance with respect to said resistance in series with the grid, and means for supplying a controlling potential through said resistance to the control grid comprising a source of potential, and variable control means therefor, for varying the control grid potential in a positive direction, thereby to broaden the tuning response characteristic of said tuned circuit. 50 55

4. In a radio frequency amplifier, a tuned high frequency circuit, an electric discharge amplifier device having a control grid connected therewith for receiving signals therefrom, an electric discharge device having an anode connected to the high potential side of said tuned circuit and a cathode connected with the low potential side thereof, the anode circuit of said device being completed through an inductance element in 70 75

said tuned circuit, and said device further having a control grid coupled to the high potential side of said tuned circuit and connected conductively with a source of biasing potential, and means inserted in circuit therewith for varying the biasing potential applied to said control grid whereby the mutual conductance of said device is varied in response thereto, thereby to vary the loading applied to said tuned circuit in proportion to the strength of received signals and in proportion to the adjusted mutual conductance of said device.

5. In an intermediate frequency amplifier for a superheterodyne receiver, an intermediate frequency amplifier coupling transformer having a 15 tuned primary winding, a pair of electric discharge amplifier devices each having a control grid, and an anode circuit completed through said primary winding, means for applying intermediate frequency signals to the control grid 20 of one of said devices comprising a separate intermediate frequency input circuit, means for applying to the control grid of the other of said tubes a variable biasing potential, thereby to 25 adjust the mutual conductance thereof, the range of variation being such that the variation range is extended to a value whereby the tuned circuit is loaded with a resistance below 1,000 ohms in value, and means including a coupling condenser for coupling the last named control 30 grid to said tuned primary winding.

6. In a radio receiving system, the combination with a tuned signal circuit comprising a winding of a coupling transformer, an electric discharge amplifier device connected with said winding for the transmission of signals therethrough, a second electric discharge device having an anode circuit including said winding in common with said tuned circuit, a cathode, and a suppressor grid, a screen grid and a control grid in the order named between the anode and said cathode, means for coupling said control grid to the tuned circuit, said means including a condenser of relatively low capacity connected between the high potential side of said tuned circuit and said 45 grid, and a grid leak resistor connected to the grid, the reactance of the condenser being less than a low percentage of the resistance of the grid leak resistor, means for applying a fixed negative biasing potential to the control grid, 50 and means for applying a control voltage to said grid which varies with variations in signal strength, the direction of variation being such that the mutual conductance of the last named device is varied through a range providing a relatively wide change in the effective plate impedance of said device whereby the selectivity of the tuned circuit is varied between wide limits.

7. In a radio receiving system, the combination with a tuned signal circuit comprising a 60 winding of a coupling transformer, an electric discharge amplifier device connected with said winding for the transmission of signals therethrough, a second electric discharge device having an anode circuit including said winding in common with said tuned circuit, a cathode, and a suppressor grid, a screen grid and a control grid in the order named between the anode and said cathode, means for coupling said control grid to the tuned circuit, means for applying a potential to the control grid, and means for applying a control voltage to said grid which varies with variations in signal strength, the direction of variation being such that the mutual conductance of the last named device is varied through 65 a range providing a relatively wide change in

the effective plate impedance of said device whereby the selectivity of the tuned circuit is varied between wide limits.

8. In a radio receiving system, a tunable signal circuit including a transformer winding, an electric discharge device of the pentode type having its plate-cathode impedance connected in shunt relation to said circuit, means for varying the control grid potential of said device, means providing a connection whereby the anode current of said device flows through said winding, and means providing a signal coupling connection for the control grid of said device with the high potential side of said circuit whereby the selectivity of said circuit may be varied 15 through a wide control range by variation of said grid potential, and means providing variable potential for controlling said grid.

9. The combination with a radio signal amplifier including an electric discharge amplifier device having a tuned output circuit, of means for controlling the selectivity of said system including a second electric discharge amplifier device having an anode electrode connected with said tuned output circuit in parallel with said first named device and having a control grid coupled to said output circuit through capacity coupling means, a grid circuit for said grid having an impedance higher than the reactance value of said coupling means, and means for applying to said grid circuit a controlling potential for varying the anode-cathode impedance of said last named device, and said last named device being further provided with a screen grid between said anode and control grid.

10. In a radio signal amplifier, the combination with a tuned signal transmission circuit, of a pentode electric discharge device having its anode-cathode impedance connected substantially in shunt across said circuit as loading means therefor, means providing a high impedance grid circuit for said device, and means providing capacity coupling between said grid circuit and said signal transmission circuit at the anode side thereof, said capacity coupling means providing an impedance lower in resistance value than the resistance of said grid circuit.

11. In a radio signal amplifier, the combination with a tuned signal transmission circuit, of a selectivity control tube of the screen-grid pentode type having the anode-cathode space path thereof connected substantially across said circuit, said device having a control grid coupled to the high potential side of said tuned circuit, a coupling condenser of relatively low impedance providing said coupling, means including a high impedance grid circuit for said control grid, and means for applying to said control grid through said grid circuit a biasing potential responsive to variations in signal strength.

12. In a radio signal amplifier, the combination with a tuned signal transmission circuit of a selectivity control tube of the screen-grid pentode type having the anode-cathode space path thereof connected substantially across said circuit, said device having a control grid coupled to the high potential side of said tuned circuit, a coupling condenser of relatively low impedance providing said coupling, means including a high impedance grid circuit for said control grid, and means for applying to said control grid through said grid circuit a biasing potential of a value to cause the anode-cathode impedance of said device to fall below 1,000 ohms.
